UNITED STATES PATENT OFFICE

GEORGE J. NETH, OF DAYTON, OHIO, ASSIGNEE TO THE EGRY REGISTER COMPANY,
OF DAYTON, OHIO, A CORPORATION OF OHIO

AUTOGRAPHIC REGISTER

Application filed July 24, 1925. Serial No. 45,764.

My invention relates to autographic registers.

It is the object of my invention to provide an autographic register containing the usual plurality of sheets which are ejected from the register and realigned at the end of each ejecting operation.

It is a further object to provide means of aligning these sheets by means of file punch holes in the sheets.

In particular, it is my object to provide means of ejecting the sheets to a predetermined length and then utilizing the aligning means for both aligning and completing the ejection of the sheets.

It is my object to provide the same movement for alignment and for final ejection, irrespective of the length of tickets or forms ejected by the machine.

It is my object to provide a standard mechanism which may be simply varied for varying lengths of tickets or forms by changing the gearing actuating the ejecting rollers. Otherwise the mechanism remains the same and it is therefore capable of quantity production and standardization.

It is my object to provide an autographic register which may be operated at any desired speed, which realigns the sheets after each writing operation and places the sheets in aligned and clamped condition for writing just prior to the writing operation so that there may be no accumulated error due to the sheets getting slightly out of alignment as any such condition is corrected during each cycle of operations.

Referring to the drawings:

Figure 1 is a side elevation of the complete register;

Figure 2 is a section on the line 2—2 of Figure 4;

Figure 3 is a section on the line 3—3 of Figure 4;

Figure 4 is a plan view of the register with the writing table broken away and the covers removed and lifted;

Figure 5 is a section on the line 5—5 of Figure 9;

Figure 6 is a prospective of the front of

the cam and cam plate used to guide the pin frame in its movement;

Figure 7 is a section on the line 7—7 of Figure 4;

Figure 8 is a section on the line 8—8 of Figure 4;

Figure 9 is a section on the line 9—9 of Figure 4;

Figure 10 is a view similar to Figure 9, showing in detail the position of the pins during the aligning operation with the rollers spread apart; and

Figure 11 is a detail view of the upwardly projecting side wall lugs, showing the arrangement for allowing the upper roller to reciprocate vertically.

Figure 12 is a detail sectional view on the line 12—12 of Figure 4.

Referring to the drawings in detail, 1 is the base of a register having end walls 2 and 3. 4 and 5 designate the side walls of the register. In these side walls the shafts 6 are journaled for supporting the paper rolls 7. On the top of the register is hinged a cover 8 having an enlarged transversely disposed casing 9 above the general level of the cover, the forward end of which terminates in fingers 10 which are engaged by the lugs 11 of the forward sliding cover 12 for holding the cover in position. The side walls are extended forwardly as at 13 and are provided with slots 14 for receiving the ends of the shaft 15 of the upper roller 16 so that the roller may move upwardly and downwardly. This roller is pressed in engagement with the lower roller, if desired, by a spring 17.

The writing cover is provided with the usual writing opening not shown.

A handle 18 is provided for actuating the register, which handle is limited in its movement at the end of each cycle by the movable stop 19 pivoted at 20 on the side wall 4 of the register. It will be understood that any stop may be utilized whether it is a part of the handle or a part of the register. The handle is mounted upon the handle shaft 21 which is journaled in the side walls of the register. This shaft carries at either end cams 22 which are adapted to lift the arms 23 on either side of the register which are located

between the rolls 16 and 24 for spreading them by lifting the upper roller 16. These arms 23 are pivoted at 25 on the side walls of the register and are so arranged that they proceed forwardly to a point adjacent the rollers where they are curved upwardly and then forwardly, terminating in a projecting forward end 26. This end is engaged by a sliding plate 27 which has slots 28 and pins 29 therein, which pins are carried by the side wall of the register. The lower end of the plate 27 is formed with a foot 30 which rests upon a cam rod 31 which has a flat face 32 on one portion of its periphery. When this 10 rod is rotated the plate 27 is lifted which in turn lifts the end 26 of the lever 23. This arrangement is provided for on both sides so that both levers are simultaneously elevated with the result that the roller is elevated and maintained in elevated position as long as desired during the adjustment of the machine or the loading of it with paper. 15

Returning to the handle shaft 21, mounted on this shaft is a main actuating gear 33. This actuating gear meshes with a pinion 34 mounted on a stub shaft 35 in the inside of the register. This pinion in turn meshes with the gear 36 mounted on the lower roller shaft 37 which is journaled in the side wall 20 of the register. The gear 36 operates the gear 38 on the upper roller 16. The gear 38 is mounted on the shaft 15 of the upper roller. Similar gears 36 and 38 are found on both ends of the roller shafts so that the rollers 25 turn in unison. These rollers are knurled at their central portions and are provided with cut away slots or grooves 39 and 40 to accommodate the pins 41 as will be hereinafter pointed out. The shaft 21 also carries a gear 42 which meshes with a gear 43 on a shaft 44. This shaft is supported on plates 45 which are also supported on the handle shaft 21 and a transverse rod carried in the side walls of the register designated 46. On 30 the ends of the shaft 44 are plates 47 on the margins of which are located studs 48 for the pivotal mounting of the pitmen 49. Each pitman carries at its outer end a cam follower pin 50. On this pin is also mounted the arm 51 which is connected to the pin frame 52. The pitman 49 is an arched member so that it will clear the shaft 21. The pin 50 travels in the cam slot 53 formed by the aperture 54 in the plate 45 and the cam member 55 carried on the cam plate 56 which forms the back of the slot. This cam plate is pivoted at 57 to the plate 45. The pin 50 travels in the slot in the direction of the arrow during the 35 operation of the pin frame starting from the point designated 58 and returning to that point. When it returns to that point it must pass by the gate 59 of the cam, thereby lifting the cam 55 and the cam plate 56 about its pivotal point 57. As the pin 50 rides up on the cam face 60 the pin frame 52 is carried up-

wardly at its pin end. As the pin 50 travels on the horizontal surface 61, the pins 41 being in engagement with the paper, move the paper forwardly to the last step in the stroke, delivering the paper in aligned condition to the final position where the rollers reengage it, the rollers having been separated from the paper during this operation as will be hereinafter explained. When the pin 50 descends through the vertical portion of the slot at 62, then the pins 41 are being withdrawn from the paper. When the pin 50 travels through that portion of the slot designated 63, the pins and pin frame are being restored to the initial position which is engaged by the pin 50, getting to the position 58. 70

Turning to the pin frame, it will be observed that it consists of a U-shaped member 64 and that on one side of one of the parallel members of the U frame is mounted the pin 41. There are two of these frames for two pins, but the number of pins is immaterial, although I prefer two pins to fit in the file punch holes normally found in register sheets. The forward end of the frame is provided with a slot 65 in which is located the transverse shaft 66. Retaining washers 67 prevent lateral movement of the frame members 52. The frame members with the pins are caused to reciprocate by reason of the connection of the pitman 49 to the arm 51 of the frame. The inside of the free portion of the U member 68 which carries the pin 41 rides on the top of the shaft 37 in the slot 40 in the lower roller. 75

In Figure 9 the pins are shown just in the position when they have been withdrawn from the holes in the paper and the paper sheets have been reclamped by the rollers. 80

The plate 56 is returned to its initial position when moved by the pin 50 due to the fact that a spring 69 connected thereto as at 70 and which has its other end at 71 connected to the plate 45. 85

Method of operation

Assuming the sheets have just been written upon and are therefore clamped at their forward end by the rollers, and assuming that the handle is in the position at rest against the handle stop, the operation of this mechanism is as follows. 90

As the handle rotates the gears 33, 34, 36 and 38 will rotate due to the actuation thereby from the shaft 21, thus ejecting the sheets until the sheets are within approximately $\frac{1}{4}$ inch of the end of their movement at which time the high points of the cams 22 on the shaft 21 of the handle go beneath the levers 23, lifting them and separating the rollers so that the sheets are no longer actuated by the rollers. At this moment the pin parts come into operation. The parts are in the position shown in dotted lines in Figure 9 with the pins just beneath the holes in the paper about $\frac{1}{4}$ inch. 95

inch to the rear of the rollers. The pin 50 is in the position designated 58. At the beginning of the stroke the pin and parts were in the position as shown in Figure 9, but by this time they have returned to the position shown in dotted lines. As the handle continues to turn, due to the fact that the pin frame and its associated parts are actuated through the pitmen 49, plates 47, shaft 44 and gears 42 and 43, the pin 50 travels upwardly on the face 60 of the cam 55, elevating the pins and pin frame, pushing the pins into the holes in the paper to align the paper sheets. This aligning operation and pin insertion operation is completed when the pin 50 gets to the top of the cam 55 on the horizontal top portion 61. It then travels forwardly on 61 at which time the pins are in the paper and serve to move the sheets forwardly in aligned condition until the pin 50 gets over the vertical slot 62 at which time the pins are in their forwardmost position between the rollers. They then drop down to the position shown in full lines in Figure 9 and just prior thereto the high points of the cams on the shaft 21 which have held the levers 23 elevated and have held the upper roller also elevated come to an end and allow the upper roller to drop with its arms 23, thus reclamping the paper and holding the paper in aligned position for the writing operation. In Figure 12, the parts are shown just before the final movement which permits this operation.

It will be understood that I desire to comprehend within my invention such modifications as may be necessary to adapt it to varying conditions and uses.

Having thus fully described my invention, what I claim as new and desire to secure by Letters Patent, is:—

1. In an autographic register having a plurality of sheets with spaced perforations, an actuating handle, a handle shaft, upper and lower ejecting rollers, means to operate said rollers from said handle shaft, means to spread said rollers, means on said handle shaft to operate said spreading means during a predetermined interval, a pin frame adapted to reciprocate pins mounted thereon, means actuated by said handle shaft to reciprocate said pin frame and moving said frame and pins with said paper forwardly to move said paper to final aligned position, and means carried on the register engaging with said pin frame for moving the pins into engagement with the paper sheets, moving the sheets forwardly to clamping position, withdrawing the pins and restoring the pins and the frame to the initial position for another operation of alignment.

2. In an autographic register having a plurality of sheets with spaced perforations, an operating handle, a shaft, a pair of ejecting rollers geared together and geared to the shaft operated by the handle gearing for

that purpose, interconnecting said shaft and rollers, cams mounted on said shaft adapted to lift roll spreading arms, said roll spreading arms pivotally mounted on the register and extending between the rollers, a second shaft parallel to the handle shaft, gearing connecting said shafts, levers on the end of said second shaft, pitmen connected thereto on the ends thereof, reciprocating pin frames connected thereto on the free ends thereof, means to support said frames at one end, means on said frames for reciprocating in grooves in one of said rollers to support the other end of said frames, pins mounted on said frames to reciprocate in said grooves, means to support a movable cam member, said means having a slot around said cam to form a cam slot, a plate pivotally mounted on said means for carrying said cam, yielding means to maintain said cam in its normal position, and means on said pin frame engaging in said cam slot and with said cam, whereby as the handle shaft is rotated the pitman will reciprocate and the pin will move the pin frame and pins upwardly for the pins to engage with the sheets, forwardly to pull the sheets forward by the pins to clamping position, downwardly to remove the sheets from the pins, and rearwardly to the initial starting position in a single cycle of operations, said roll spreading cams operating to spread the rollers during the period the pins are being inserted in the paper, moving the paper forwardly and are being withdrawn from the paper.

3. In an autographic register, a handle, a handle shaft, a pair of ejecting rollers, one of which is movable away from the other gearing to drive said rollers from said shaft to connect the rollers to one another to turn together, cams on either end of said shaft for operating roller spreading arms, said roller spreading arms located between said rollers and pivoted on said register, a second shaft parallel to the handle shaft, gearing connecting said shafts, spaced pitmen operated by said second shaft, reciprocating pin frame members connected to the respective pitmen, a transverse member working in slots in said reciprocating pin frame members for supporting one end thereof, an arm depending from each of said pin frame members connected to said pitmen, U-shaped ends for said pin frame members, a pin mounted on the outside of the free portion of the U-shaped members of the pin frames, the under side of said arms being supported on the lower roller shaft of the lower roller in slots in said rollers, a third shaft parallel to the handle shaft, plates carried thereby having cam slots, a cam carried on a cam plate projecting into said cam slot, said cam plate being pivotally mounted on said first mentioned plate, yielding means for maintaining said plate in normal position, a pin on each of

said pitmen and pin frames working in said cam slots, said cam slots being so arranged that the pin frames and pins will be moved in a rectangular path substantially for successive operations of the pins entering the paper sheets, moving the sheets forwardly, withdrawing from the sheets and returning to initial position.

4. In an autographic register having a plurality of sheets with spaced perforations, a handle, a removable stop therefor, a handle shaft, a master gear thereon, upper and lower ejecting rollers having grooves therein, gearing on said rollers, gearing between said rollers and said master gear for operating it, a pair of spaced pin frame members consisting of a horizontally disposed portion, one end of which contains a slot and the other end of which contains a U-shaped member horizontally disposed, the upper arm of the U-shaped member resting on the lower roller shaft in a groove therein, a pin mounted on the upper arm of said U-shaped member adapted to reciprocate in the groove, depending arms from the under sides of said U-shaped members, arch shaped pitmen pivotally connected thereto, the other end of said pitmen being connected to plates, a common shaft on which said plates are mounted, gearing to operate said shaft from the handle shaft, a third shaft, spaced plates carried on the handle shaft and the third shaft, said plates having cam slots therein, a pin on each of said pitmen at the pivotal point of connection with the pitman to the depending arms of the pin frames, said pins working in said cam slots, a cam projecting in each of said cam slots, a plate carrying said cam pivotally mounted on said first mentioned plate, yielding means for maintaining said cams in normal position, said cams consisting of rectangular portions with a depending finger at one end, spaced cams on said handle shaft having high points, roller spreading arms on either side of said register pivoted thereon having upwardly and forwardly projecting fingers inserted between the rollers and adapted to be operated by said last mentioned cams on the handle shaft, whereby in a single revolution of the handle the sheets will be ejected to a predetermined point at which time the rollers will be spread, the pins inserted, the sheets pulled forwardly by the pins to a point between the rollers, the pins withdrawn and the sheets reengaged by the rollers.

In testimony whereof, I affix my signature.
GEORGE J. NETH.
